by A. S. Johnson
her Attorney.

UNITED STATES PATENT OFFICE.

ANNA L. R. JOHNSON, OF MARIETTA, MINNESOTA.

CARD GAME.

Application filed March 27, 1922. Serial No. 547,026.

To all whom it may concern:

Be it known that I, ANNA L. R. JOHNSON, a citizen of the United States, residing at Marietta, in the county of Lac qui Parle and State of Minnesota, have invented certain new and useful Improvements in Card Games, of which the following is a specification.

This invention relates to card games, and 10 more particularly to improvements in a pack of playing cards, an object of the invention, being the provision of cards for a card game specially adapted to be played by school children.

15 To this end, I provide a pack of cards representing a plurality of divisions or sections, each division consisting of an equal number of cards. Each of the divisions has a different identifying name, which name 20 is a word having a meaning calculated to awaken in the mind of the player, a thought of some phase or thing common to school life, such as Teacher, Grammar, Busy work, and the like. In turn, each of the cards 25 constituting a division, bears different data in the form of either, a word, phrase, a simple sentence, an exclamation, a question, or any other suitable expression having direct or indirect relation to the meaning of the 30 name of its division. For example, each of the cards of the division named "Teacher" bear one of such inscriptions as, "That's splendid", "No whispering", "In your seats", "See how good John is", and the like, while 35 the cards of the division named "Grammar" carry such words as "Noun", "Pronoun", "Verb", "Analysis", "Syntax", and so forth.

40 Thus, the expression "That's splendid", will beneficially exercise the mind of the player to quickly trace the source from which such an expression is likely to emanate. Obviously, to the mind of a player, going or having gone to school, the name 45 "Teacher" would be the most suggestive.

Likewise, the division "Grammar" is easily recalled by such words as "Noun", "Verb", and the like, as the words are directly related thereto.

50 It is an object of my invention, to provide an amusing card game, which will

pleasantly exercise the memory of the player, both young and adult, inasmuch as, during the progress of the game, knowledge long forgotten is repeatedly called to mind. 55

My invention, in its preferred form, is illustrated in the accompanying drawings, which form a part of this specification and in which:—

Figure 1, represents a front view of one 60 division of a pack of cards in accordance with my invention.

Fig. 2, represents a front view of another division of the pack, the data being placed longitudinally thereof to facilitate 65 illustration, and

Fig. 3, represents an index card disclosing the identifying letters of the sets constituting the divisions.

The cards are designated by the numeral 70 1 and may be of any suitable material and size, but are preferably of the shape and size of ordinary playing cards, there being five cards for each letter of the alphabet, excepting the letters Q—T—W—X—Y— 75 and Z, thus making a total of one hundred cards in the pack. These are preferably divided to form ten divisions of ten cards each, each division comprising two sets of five cards each, all of the sets in the pack 80 carrying distinctive identifying marks 2, whereby the cards of each set may be readily recognized. The distinctive mark is preferably placed at diagonally opposite corners of the cards, but may be placed at 85 the four corners if desired. The identifying marks 2, consists of the twenty letters of the alphabet referred to in the foregoing and to be hereinafter referred to as distinctive set or book identifying marks, the two 90 divisions illustrated in Figs. 1 and 2 of the drawings, bearing the identifying imprints of the letters A—B and C—D respectively. The index card 4 is provided, whereby the letters identifying the sets of the several 95 divisions may be readily ascertained, to be memorized by the players.

Of the ten divisions indicated on the index card, the names and appropriate data relating respectively thereto, of the first 100 two divisions is disclosed in Figs. 1 and 2 of the drawings. These two divisions are

typical of all the rest, which latter are here briefly recited to set forth the variety of subject matter which may be brought to the mind of the players.

5 In playing the game for which the cards are specially intended, eight cards are dealt, one at a time, to each player, of which there may be four, more or less as desired. When less than four play, some 10 of the divisions may be taken out of the pack, or when small children play, such divisions as "Grammar"—Geography and Spelling may be extracted.

15 In the play, three cards bearing the same book mark, constitute a group, while five constitute a book. The players endeavor constantly to score counts by being the first to name the division to which a group belongs, and to complete the largest number 20 of books. The manner of accomplishing this, is clearly set forth in the following description of the plays and rules of the game.

25 When three or more play (the cards having been dealt as stated in the foregoing) the players, beginning with the dealer, and progressing leftward from one to the other, is given a chance to announce that he holds a group in his hand. The player holding 30 the group, immediately reads aloud, the data of one card of the group. All the players are now permitted to name the division to which the card belongs. The player who makes the first announcement 35 is first recognized and if he names the proper division is credited with two points in his score. Should he, however, name the wrong division, he is penalized two points, and the player holding the group, lays them, 40 face up, upon the table, and draws a card from the pack left over after dealing. If this player has another group he does as before. If not, he passes an undesirable card to the player on his left and draws 45 another card from the pack. He is now estopped from further play, even though the last card drawn, completes a group in his hand, or could be played by adding it to the group which he previously laid on the 50 table. The players to his left, in turn, are given the same opportunity as the first player, to announce the holding of a group, and call for the division, or if they have no group but have a card of the same book 55 mark, as the group or groups on the table, as the case may be, they may play such cards in the endeavor to complete books or play the fourth card thereon. If no player in turn holds a group or book in the hand, the 60 player to the left of the dealer, passes an undesirable card to the player at his left, and then draws a card from the pack. If the player to his left, to whom he passed the undesirable card, now has a group, he duplicates the play described in the foregoing, 65

namely, names a card, of his group and calls for a division, lays the cards face up upon the table and draws a card from the pack. If the card drawn does not complete a group in his hand, but makes a fourth or 70 fifth card of a book with reference to the cards on the table, he must place it on the latter, pass a card to the player on his left and draw a card from the pack. If the next player, after receiving the card, holds the 75 fifth, or the fourth and fifth cards, of the book begun which is lying on the table, the book is his which he takes as a trick for scoring, and he then draws a card from the pack. If he then has a group he repeats 80 as before. He is entitled to play as long as he holds a group, can finish a book, or is able to play a fourth card in the formation 85 of a book, after which he passes a card to the player at the left and draws one from the pack. If player holds in his hand no card to pass on, he plays no more until cards are dealt again. If the game is blocked so 90 no player can continue according to rules, count points gained by each, and if no one has fifty or more deal cards again as before. The game progresses in this manner until all the cards have been made into books.

95 Summarizing, a card is drawn, when the player has a group, completes a book, and after passing a card to the player on his left. No card is drawn after the fourth card is played, but this card, if a drawn card, must be played as soon as drawn, unless it is drawn after the player has passed a card to the player on his left. Further, this fourth card must be played when this player plays the next round. For not playing the card thus, the player is penalized 100 one point.

105 The score for each player consists of the sum of the books completed in play, or held in the hand, plus the credits won by naming the correct divisions, minus the penalties imposed. The player first making fifty points wins the game.

110 All of the legible printed matter carried by the cards, has relation to school instrumentalities, but it is to be understood that the fundamental principle involved in my invention, may be applied to other organized instrumentalities.

I claim:

12 1. Card game apparatus, comprising a deck of cards divided into groups, legible means on each card to suggest but not name a group to which the card belongs, a character on each card, alike for all cards in a group but distinctive for different groups, and an index containing a list of the group designating characters, and in conjunction with each group designating character the name of the group which it designates.

125 2. A pack of cards, divided into a plu-

rality of equal divisions, each division being assigned a different name, each name having some relation to school instrumentalities, different legible printed matter on each card, said printed matter on the cards having special relation to the names of the respective divisions to which they belong, a

mark for each card whereby to identify the division to which it belongs, and an index card bearing the names of all of the divisions and the marks of the cards comprising the respective divisions.

In testimony whereof I affix my signature.

ANNA L. R. JOHNSON.
